CLOSED RECEPTACLE OR CASE

Merrill L. Rathbun, Salamanca, N. Y.

Application July 29, 1939, Serial No. 287,352

3 Claims. (CL 217—57)

This invention relates to an improvement in closed receptacles or cases and more particularly to receptacles comprised of more than two elements.

The invention is more specifically directed to a closed receptacle having suitable base and cover elements that together completely enclose the space therewithin. The base and cover elements are pivotally connected in a manner similar to that disclosed in my Patent #1,833,305. One or more intermediate elements may be located in the receptacle to divide it into two or more compartments. The intermediate element may be pivotally joined to either the base or cover element and is operable to expose or close a compartment when the receptacle is open, and is provided with independent hinge means. It is intended that one or more intermediate elements of this nature will serve to divide the interior of the receptacle into several compartments, thereby adapting it to a variety of uses.

The receptacle illustrated and described is produced from a moldable substance, but it will be understood that the material from which the receptacle is formed has no bearing on the invention, inasmuch as wood, metal, or any other suitable substance may be used with equal satisfaction in practicing the invention.

One of the objects of the invention lies in the provision of a closed receptacle having one or more elements that serve to divide the interior into two or more compartments.

Another object of the invention lies in the provision of a closed receptacle having an interior compartment forming element pivotally connected with either the body or cover element of the receptacle.

Another object of the invention lies in the provision of an intermediate compartment forming element for a closed receptacle that is pivotally connected with either the receptacle body or cover and includes spring means for retaining it in opened or closed position.

Another object of the invention lies in the provision of a closed receptacle having pivotally connected spring actuated body and cover elements, within which is located one or more compartment forming elements having hinge connection with either or both the body and cover, the element pivotal connection being independent of the body and cover pivotal connection.

Other objects and advantages of the invention will be more fully understood from a consideration of the following specification, taken in con-

junction with the accompanying drawings; and in which

Figure 1 is a perspective view of one modification of the invention showing a receptacle cover in fully opened position and an intermediate element in partially opened position;

Figure 2 is a plan view of the receptacle with the cover in closed position, parts being broken away to disclose certain details of structure;

Figure 3 is an enlarged vertical sectional view of the receptacle, being taken substantially on the line 3—3 of Figure 2;

Figure 4 is a further enlarged vertical sectional view, being taken substantially on the line 4—4 of Figure 2;

Figure 5 is an enlarged fragmentary vertical sectional view showing the cover and intermediate elements in opened position;

Figure 6 is an exploded vertical sectional view of the body, cover, and intermediate elements showing the method of assembly;

Figure 7 is a perspective view of a receptacle in opened position showing a modification of the invention as disclosed in Figure 1;

Figure 8 is an enlarged fragmentary plan view of the receptacle in closed position, parts being broken away to disclose certain details of structure;

Figure 9 is a vertical sectional view of the receptacle, being taken substantially on the line 9—9 of Figure 8;

Figure 10 is a vertical sectional view of the receptacle, being taken substantially on the line 10—10 of Figure 8;

Figure 11 is a fragmentary vertical sectional view showing the cover and intermediate elements of the receptacle in opened position; and

Figure 12 is an exploded view of the elements of the receptacle illustrating the method of assembly.

Reference is now had to Figures 1 to 6, inclusive, of the drawing wherein one modification of the invention is embodied in a closed receptacle generally indicated by the reference numeral 10. The receptacle comprises a body 11 and cover 12. The rear or hinge wall 13 of the body 11 is reinforced or of thicker proportions than the other walls thereof.

The upper edge of the wall 13 is formed with a bead 14. In the present disclosure the bead is formed in two parts, one adjacent each end of the wall 13. The bead may be rearwardly offset substantially as shown to provide a considerable degree of opening of the cover 12, this being clearly illustrated in the drawing. Midway of

the length of each bead 14 is a recess or slot 16 that continues downwardly of the body, having a curved base wall 17 that terminates in a spring seat 18. The wall 17 is preferably formed in a predetermined curve, or may be provided with a suitable projection on the surface thereof to constitute a stop to limit movement of the cover 12 by contact with a strap spring that forms a part of the pivot hinge structure.

The cover 12 is formed with a reinforced rear wall 19, the lower edge of which has a recess or seat 21 which receives and is complementary to the bead 14. The seat 21, in the present disclosure, is interrupted centrally of the wall 19 to the same extent as the bead 14. A recess 22 opens into each seat thus formed midway of their length, being provided with a curved base wall 23 that terminates in a spring seat 24. The curved wall 23, as indicated in Figure 5, cooperates with the wall 17 to form a continuous curved surface with which a strap spring contacts to limit the extent of opening of the cover. A spring 26, having flanged ends 27, is mounted in the aligned recesses 16 and 22 of the body and cover, the ends 27 engaging spring seats 18 and 24.

In the present illustration of the invention the rear wall 13 of the body portion is of thicker proportions than the rear wall 19 of the cover and includes, intermediate the ends of the wall 13, an upstanding portion 28 that terminates in its upper edge in a bead 29. Centrally of this bead is a recess 31, having a curved base wall 32 that terminates in a spring seat 33.

An intermediate element 34 is provided for the purpose of dividing the interior of the receptacle into two compartments, or it may serve as a shelf or ledge on which to mount jewelry or other articles for display. It is also contemplated that the element may be formed with one or more recesses or openings into which articles may be set and secured against displacement. If, as shown in the present modification, the element 34 is positioned to form a cover to the bottom portion 11 of the receptacle, a central, raised, reinforced portion 36 is provided. The lower edge of the portion 36 is formed with a recess 37 that is complementary to the bead 29. The portion 36 may be formed with a cavity 38, the base wall 39 of which terminates in a spring seat 41. When the seat 37 of the element 34 is engaged with the bead 29, a strap spring 42 may be utilized to secure these elements in operable pivotal relationship. This spring includes ends 43 that are engageable with seats 33 and 41. The curved surfaces 32 and 39 cooperate to form a continuous curve with which the spring 42 engages when the element 34 is moved to opened position with respect to the body portion 11 (see Figure 5).

The pivot hinge construction of the body and cover 11 and 12, as well as that of the body and intermediate element, is such that midway between opened and closed position the springs 26 and 42 are on dead-center. Thus, these springs serve to retain the cover 12 and element 34 in either fully opened or closed position. The position of the element 34 in Figure 1 is merely illustrative of the structure of the invention.

The bead 29, serving as part of the hinge structure for the element 34, may be formed in or secured to the rear wall 19 of the cover 12, in the event it is desired that the element 34 cooperate with the cover rather than the base to form a closed compartment. While this structure is not specifically shown, it can be readily understood by inverting the drawings and examining Figures 75

3 and 4. It will be further understood that either or both beads 14 and 29 may be applied to the cover rather than the body in certain types of receptacles wherein such structure is more suitable.

Reference is now had to Figures 7 to 12, inclusive, of the drawings wherein a further modification of the invention is shown. In this instance a receptacle is shown, being generally indicated by the reference numeral 46. The receptacle comprises a body 47 and cover 48. The rear or pivot hinge wall 49 of the body is reinforced adjacent its ends and is formed with two somewhat outwardly projecting beads 51. Between the ends of each bead is a downwardly opening recess or slot 52, having a curved base wall 53 that terminates in a spring seat 54. The cover 48 is formed with a reinforced rear wall 56, the lower edge of which has two short recesses or seats 57 that are complementary to the beads 51 of the body 47. Centrally, each of the seats is interrupted by a vertical recess 58 having a curved base wall 59 that terminates in a spring seat 61. When the body and cover are engaged with the beads 51 resting in seats 57, strap springs 62 are applied for the purpose of securing the elements of the receptacle in operable pivotal relationship. Each of the springs 62 has ends 63 engageable with the spring seats 54 and 61. As in the modification above described, the curved surfaces 53 and 59, when the cover is in opened position, cooperate to form a continuous curved surface with which the body of the spring 62 contacts to limit the extent of opening of the cover with respect to the body.

Midway of the rear wall 49 of the base 47 is a further reinforcement 64. This portion is formed with a semi-circular recess 66 on its upper edge, which is interrupted midway of its length by a slot 67, a part of the base wall 68 of which is curved and terminates in a spring seat 69.

An intermediate element 71 is adapted to form a cover for the body 47 and divides the interior of the receptacle into two compartments. As in the previous modification, it may also serve as a shelf or ledge on which to mount articles, such as jewelry, for display purposes. Adjacent the front wall of the body 47 corner ledges 72 may be provided that serve to seat the forward end of the element 71 substantially flush with the upper edge of the body 47. The rear edge of the element 71 is formed with a bead 73 that projects downwardly and is complementary to the seat 66. A downwardly opening recess 74, adjacent the bead 73, provides a spring seat 76. In line with the seat 76, the bead is cut away to provide a spring receiving recess or slot 77. A strap spring 78 is adapted to secure the element 71 in operable pivotal engagement with the body 47, the ends of the spring engaging seats 69 and 76. When element 71 is moved to opened position (see Figure 11) the curved wall 68 and the base wall of slot 77 cooperate to form a continuous curved surface with which the central portion of the spring engages and acts to stop further pivotal movement of said element.

It will be apparent that the intermediate elements shown in the modifications of the drawings, namely, 34 and 71, may be of any contour and may or may not serve as closures for the body of the receptacle. It is contemplated that these elements may be ornamental, of different contour, and the body and cover elements of the receptacle may also vary in their proportions.

Other variations and modifications than those

indicated are also contemplated in the application of the invention to receptacles for various uses and insofar as they are within the spirit and scope of the invention as defined in the hereunto annexed claims.

Having thus set forth my invention what I claim as new and for which I desire protection by Letters Patent is:

1. In a receptacle having body and cover elements pivotally joined together, a reinforced portion adjacent the pivotal jointure of said body and cover elements, an intermediate element within said receptacle, complementary pivotal means on said portion and said intermediate element, spring seats formed in said portion and said intermediate element and a spring engaged with said seats, said spring serving to secure said intermediate element in operable pivotal relationship with said portion and yieldingly urge said intermediate element into open or closed position with respect to one of said receptacle elements.

2. In a receptacle having body and cover elements pivotally joined together, an intermediate element located within and being enclosed by the body and cover elements of said receptacle, a reinforced portion in the body element ad-

10 jacent the pivotal jointure of said elements, complementary pivotal parts on said portion and said intermediate element, spring seats in said portion and said intermediate element adjacent said parts, a spring engaged with said seats and securing said parts in operable pivotal relationship, and means cooperating with said spring to limit the extent to which said intermediate element may be pivotally moved with respect to the body element of said receptacle.

15 3. In a receptacle having body and cover elements pivotally joined together, a reinforced portion in a wall of one of the elements of said receptacle, an intermediate element within said receptacle, complementary pivotal means on said portion and said intermediate element, spring seats formed in said portion and said intermediate element and a spring engaged with said seats, said spring serving to secure said intermediate element in operable pivotal relationship with said portion and yieldingly urge said intermediate element into open or closed position with respect to one of the elements of said receptacle.

MERRILL L. RATHBUN.

CERTIFICATE OF CORRECTION.

Patent No. 2,292,476.

August 11, 1942.

MERRILL L. RATHBUN.

It is hereby certified that error appears in the printed specification of the above numbered patent requiring correction as follows: Page 3, second column, lines 16 to 18, claim 3, strike out "spring seats formed in said portion and said intermediate element,"; and that the said Letters Patent should be read with this correction therein that the same may conform to the record of the case in the Patent Office.

Signed and sealed this 29th day of September, A. D. 1942.

Henry Van Arsdale,
Acting Commissioner of Patents.
